LIQUID-COOLED SMOKING PIPE

Donald C. Jackson, Kimberley, British Columbia,
Canada

Application July 28, 1950, Serial No. 176,399

2 Claims. (Cl. 131—173)

1

This invention relates to a water-cooled smoking pipe.

An object of this invention is to provide a water-cooled smoking pipe in which the smoke, in passing from the tobacco bowl to the mouth of the user, is conducted through a water-containing reservoir.

Another object of this invention is to provide a water-cooled smoking pipe which is adapted to purify and cool smoke as it passes from the tobacco bowl to the mouth of the user.

A further object of this invention is to provide a smoking pipe having a liquid-containing reservoir for filtering and cooling smoke as it passes from the tobacco bowl to the mouth of the user, in which the reservoir is readily accessible for cleaning and filtering.

A still further object of this invention is to provide a water-cooled smoking pipe which is simple in structure and cheap to manufacture.

Other objects of the invention will become apparent upon consulting the drawings in conjunction with the following specification.

In the drawings:

Figure 1 is a top plan view of the water-cooled smoking pipe of the present invention;

Figure 2 is a sectional view taken along the line 2—2 of Figure 1;

Figure 3 is a fragmentary sectional view taken along the line 3—3 of Figure 2;

Figure 4 is a fragmentary sectional view taken along the line 4—4 of Figure 2;

Figure 5 is a side elevational view, with parts broken away and in section, of a modification of the water-cooled smoking pipe of the present invention;

Figure 6 is a fragmentary sectional view taken along the line 6—6 of Figure 5.

Referring now more particularly to the drawings, wherein like reference numerals have been used throughout the several views to designate like parts, there is shown the water-cooled smoking pipe of the present invention, generally designated by the numeral 10, which includes a hollow pipe body 11, a bowl 12 supported within said body adjacent one end thereof, a liquid-containing reservoir 13 supported within said body in side-by-side spaced relation with respect to the bowl 12 and in communication with the latter, and a pipe stem 14 extending from the body 11 and having one end in communication with the liquid-containing reservoir 13.

The pipe body 11 may be fabricated of metal, plastic, glass or wood, and includes a bottom wall 15, a top wall 16 disposed in spaced parallel

2

relation with respect to the bottom wall 15, and a side wall 17 extending between the top and bottom walls and secured thereto. The top wall 16 adjacent one end thereof is provided with a circular opening 23. Fixedly secured to the bottom wall 15 of the body 11 below the aperture 23 is a supporting ledge 18 which is provided with a threaded aperture 19.

Extending through the opening 23 and resting on the ledge 18 is the bowl 12 which is preferably fabricated of briar. The upper open end of the bowl 12 is provided with an outwardly extending, annular flange 20 which rests upon the portion of the top wall 16 contiguous to the opening 23. The closed bottom of the bowl 12 is provided with a counterbored aperture 21 which is disposed in alignment with the threaded aperture 19 provided in the ledge 18. Extending through the aligned apertures 19 and 21 is a nipple 22 having a flange 24 adjacent one end thereof adapted to seat in the counterbored aperture 21. The other end of the nipple 22 is exteriorly threaded and in engagement with the threaded aperture 19.

Extending through the top wall 16 of the body 11 and resting upon the bottom wall thereof is an open-ended cylinder 25 which cooperates with the adjacent portion of the bottom wall to form the reservoir 13 for the reception of water or the like. The upper open end of the cylinder 25 is provided with a closure cap 26 which is exteriorly threaded and in engagement with the oppositely threaded interior portion of the reservoir 13. Accordingly, when the bowl 12 is detachably secured within the opening 23, and the cap 26 is in closing relation with the upper open end of the reservoir 13, the body 11 of the pipe 10 is closed and forms a chamber 27 for the reception of smoke from the bowl 12.

Disposed longitudinally of the reservoir 13 and secured therein is an inlet conduit having its upper end open and its lower end closed. The upper end portion of the conduit 30 is bent to form a U-shaped loop 31 disposed transversely of the reservoir 13 beneath the cap 26 and spaced therefrom. The upper open end of the conduit 30 is in communication with the smoke chamber 27 and is seated with a complementary aperture 32 extending through the wall 25 of the reservoir 13. The lower end portion of the conduit 30 is bent to form a transversely extending loop 33 positioned adjacent to and spaced from the bottom of the reservoir 13. The loop 33 is provided with a plurality of apertures 34 on the upper face thereof for the discharge of smoke therefrom into the water-containing reservoir 13.

Disposed in side-by-side spaced relation with respect to the loop 31 on the upper end of the conduit 30 is a U-shaped, open-ended, outlet conduit 35 having one of its open ends slidably received and supported within a complementary aperture 36 in the bounding wall of the reservoir, and having the other of its open ends turned downwardly for the ingress of smoke therethrough after the smoke has passed upwardly through the water-containing reservoir 13.

Disposed transversely of the reservoir 13 adjacent to and spaced below the outlet conduit 35 and supported on an annular flange 38 extending inwardly from the wall 25 of the water-containing reservoir 13 is a porous filtering element 39. The filtering element 39 minimizes the possibility of any of the liquid contained within the reservoir 13 reaching the mouth of the user while smoking.

Extending outwardly from the body 11 adjacent the supported end of the outlet conduit and in communication with the latter is the pipe stem 14 which has its outer end provided with a mouthpiece 40.

During actual use, the smoke passes from the tobacco-containing bowl 12 through the nipple 22, upwardly through the smoke chamber 27 into the looped upper end portion 31 of the conduit 30, downwardly through the conduit 30 and through the apertures 34 into the liquid-containing reservoir 13, upwardly through the liquid-containing reservoir 13 through the filtering element 39 and into the outlet conduit 35, and thence to the mouth of the smoker through the stem 14. Accordingly, it is readily apparent that, during its passage from the tobacco bowl 12 to the mouth of the user, the smoke is cleansed and cooled.

In Figures 5 and 6, there is shown a modification of the smoking pipe 12 of the present invention, which includes a bowl-shaped hollow pipe body 50 which is provided with a circular opening 51 in the upper wall thereof. Extending upwardly and rearwardly of the body 50 and secured thereto is a hollow extension 52 having one end in communication with the interior of the body 50. Detachably secured to the other end of the extension 52 and in communication therewith is a pipe stem 53. Fixedly secured to the bottom of the body 50 below the opening 51 is a supporting ledge 61.

Extending through the opening 51 and resting upon the ledge 61 is a bowl 54 which is supported within the body 50 by a nipple 55 which extends through the bottom of the bowl and the adjacent portion of the ledge 61, and is secured to the latter.

Extending upwardly and rearwardly of the body 50 in end-to-end aligned relation with the extension 52, the body 50 is provided with a circular bore 56 for slidably receiving and supporting an open-ended cylinder 57. The cylinder is detachably secured in the bore 56 by means of an exteriorly threaded closure cap 58 which engages the interiorly threaded lower end of the bore 56.

Disposed longitudinally of the cylinder 57 is a conduit 59 having its upper end supported within the cylinder 57 adjacent to and spaced from the upper end thereof. Fixedly secured to the lower end of the conduit 59 is a perforated shell 60.

In this embodiment, the smoke passes from the bowl 54 upwardly through the hollow interior of the body 50 into the upper open end of the conduit 59, downwardly through the conduit 59 and

out of the perforated shell 60 into the water-containing reservoir, upwardly through the water-containing reservoir, thence through the stem 53 to the mouth of the user. It is readily apparent that the water-cooled smoking pipe constructed according to this embodiment may be quickly disassembled for cleaning the various component parts, and that the smoke is cleansed and cooled during its passage from the tobacco bowl to the mouth of the user.

Numerous other modifications of the present invention may be made without departing from the spirit of the invention as set forth in the appended claims.

What I claim is:

1. In a smoking pipe, a closed hollow body including a bottom wall, a top wall disposed in spaced parallel relation with respect to the bottom wall, and a side wall extending between and secured to the top and bottom walls, an upstanding bowl positioned within said body adjacent one end thereof and having its lower closed end supported above and spaced from said bottom wall and having its open upper end supported on the top wall for receiving a charge of tobacco to be smoked, outlet means extending through the lower end of said bowl and having one end in communication with said bowl and having the other end in communication with the interior of said hollow body, liquid containing closed reservoir within said body formed by upstanding walls integral with the base adjacent the other end thereof and spaced from said bowl, an upstanding conduit positioned within said reservoir and having its lower end closed and adjacent to and spaced from the bottom of said reservoir and having its upper end extending through the wall of said reservoir adjacent its top and in communication with the interior of said hollow body, there being a plurality of spaced apertures in the closed lower end of said conduit for the discharge of smoke into the liquid contained in said reservoir, and a stem connected to the portion of said hollow body contiguous to said reservoir, said stem being provided with a bore extending longitudinally therethrough, one end of said bore being in communication with the top of said reservoir.

2. A smoking pipe, a closed hollow body including a bottom wall, a top wall disposed in spaced parallel relation with respect to the bottom wall, and a side wall extending between and secured to the top and bottom walls, an upstanding bowl positioned within said body adjacent one end thereof and having its lower closed end supported above and spaced from said bottom wall and having its open upper end supported on the top wall for receiving a charge of tobacco to be smoked, outlet means extending through the lower end of said bowl and having one end in communication with said bowl and having the other end in communication with the interior of said hollow body, a liquid containing closed reservoir within said body formed by upstanding walls integral with the base adjacent the other end thereof and spaced from said bowl, an upstanding conduit positioned within said reservoir and having its lower end closed and adjacent to and spaced from the bottom of said reservoir and having its upper end extending through a portion of the wall of said reservoir adjacent its top and in communication with the interior of said body, there being a plurality of spaced apertures in the closed lower end of said conduit for the discharge of smoke into the liquid contained in said reservoir, a stem connected to the portion

of said hollow body contiguous to said reservoir, said stem having a bore extending longitudinally therethrough, and a horizontally disposed conduit positioned within said reservoir and having one end in communication with said reservoir and having the other end extending through the adjacent portion of the wall of said reservoir and in communication with one end of said stem bore.
